CLAIM

The ornamental design for an earphone, as shown and described.

DESCRIPTION

FIG. 1 is a right perspective view of an earphone showing our new design;

FIG. 2 is a right side view thereof;

FIG. 3 is a left side view thereof;

FIG. 4 is a front view thereof;

FIG. 5 is a rear view thereof;

FIG. 6 is a top view thereof; and,

FIG. 7 is a bottom view thereof.

The broken line portions in the drawings are for illustrative purposes and do not form a part of the claimed design.

1 Claim, 5 Drawing Sheets
